(57) **CLAIM**

The ornamental design for a cable management hub, as shown and described.

DESCRIPTION

FIG. 1 is a top perspective view of a cable management hub for use on a table in a cable management system in a disassembled state in relationship to a table portion according to an embodiment.

FIG. 2 is a top perspective view of the cable management hub of FIG. 1 shown partially assembled.

FIG. 3 is a top view of the cable management hub.

FIG. 4 is a top view of the cable management hub with a table portion, absent a cover plate such that a plurality of cable connectors are visible within a hub well of the cable management hub.

FIG. 5 is a bottom view of the cable management hub.

FIG. 6 is a first side view of the cable management hub.

FIG. 7 is a second side view of the cable management hub.

FIG. 8 is a top perspective view of the cable management hub; and,

FIG. 9 is a bottom perspective view of the cable management hub.

The portion of the tabletop shown in FIGS. 1 and 4 are for illustrative purposes only and form no part of the claimed design.

1 Claim, 9 Drawing Sheets
